(57) **ABSTRACT**

An ejection apparatus includes: a feeding unit that feeds a recording medium; a first ejection unit that ejects droplets onto the recording medium to form plural detection images along a feeding direction of the recording medium, a detection unit that detects a distance from a predetermined origin of the recording medium to each of the detection images along the feeding direction; and a second ejection unit that is disposed on a downstream side relative to the first ejection unit in the feeding direction of the recording medium, and ejects droplets onto the recording medium at a timing based on a value obtained by adding an average value of differences between detection values of the detection unit and setting values to a setting value of the detection image on most downstream side in the feeding direction.

CROSS-REFERENCE TO RELATED APPLICATIONS

This application is based on and claims priority under 35 USC 119 from Japanese Patent Application No. 2019-072586 filed on Apr. 5, 2019.

BACKGROUND

1. Technical Field

The present invention relates to an ejection apparatus.

2. Related Art

JP-A-2004-050481 discloses an inkjet recording apparatus that performs print on a sheet by ejecting ink from an inkjet head. The inkjet recording apparatus includes: a feeding unit that feeds the sheet based on an ideal feeding amount that is a feeding amount of sheets should be fed; a detection unit that detects a difference between the ideal feeding amount and an effective feeding amount that is a feeding amount of sheets fed by the feeding unit based on the ideal feeding amount; a correction unit that determines, based on the difference detected by the detection unit, a correction amount for correcting a relative position between the sheet and the inkjet head; and a position control unit that controls a relative position between the sheet and the inkjet head based on the ideal feeding amount and the correction amount.

SUMMARY

In this regard, provided is a conceivable configuration which forms plural detection images along a feeding direction by ejecting droplets from a first ejection unit to a recording medium, which detects a distance from a predetermined origin of the recording medium to a detection image on the most downstream side along a feeding direction, and a distance between the detection images along the feeding direction, and which calculates a distance from the origin to each of the detection images along the feeding direction based on the detection value. When an ejection timing of a second ejection unit, which is disposed on a downstream side relative to the first ejection unit in a feeding direction of the recording medium, is determined based on the distance that is calculated in this configuration and is from the origin to each of the detection images along the feeding direction, a position shift may occur between an ejection position of the first ejection unit to the recording medium and an ejection position of the second ejection unit to the recording medium.

Aspects of non-limiting embodiments of the present disclosure relate to prevent the position shift between the ejection position of the first ejection unit to the recording medium and the ejection position of the second ejection unit to the recording medium, as compared with the case of detecting the distance from the origin to the detection image on the most downstream side along the feeding direction and the distance between the detection images along the feeding direction, and calculating the distance from the origin to each of the detection images along the feeding direction based on the detection value.

Aspects of certain non-limiting embodiments of the present disclosure address the above advantages and/or other

2

advantages not described above. However, aspects of the non-limiting embodiments are not required to address the advantages described above, and aspects of the non-limiting embodiments of the present disclosure may not address 5 advantages described above.

According to an aspect of the present disclosure, there is provided an ejection apparatus including: a feeding unit that feeds a recording medium; a first ejection unit that ejects droplets onto the recording medium to form plural detection 10 images along a feeding direction, a detection unit that detects a distance from a predetermined origin of the recording medium to each of the detection images along the feeding direction; and a second ejection unit that is disposed on a downstream side relative to the first ejection unit in the feeding direction of the recording medium, and ejects droplets onto the recording medium at a timing based on a value obtained by adding an average value of differences between 15 detection values of the detection unit and setting values to a setting value of a detection image on the most downstream side in the feeding direction.

BRIEF DESCRIPTION OF THE DRAWINGS

Exemplary embodiments of the present invention will be 25 described in detail based on the following figures, wherein:

FIG. 1 is a schematic diagram showing a configuration of an inkjet recording apparatus according to the present exemplary embodiment;

FIG. 2 is a schematic diagram showing plural detection 30 marks formed on a continuous sheet according to the present exemplary embodiment;

FIG. 3 is a diagram showing a method of calculating an ejection timing of an ejection head according to the present exemplary embodiment;

FIGS. 4A and 4B are diagrams showing methods of detecting each distance from an origin to each detection mark in the present exemplary embodiment and a comparative example;

FIG. 5 is a graph showing differences in effects of the 40 present exemplary embodiment and the comparative example;

FIG. 6 is a diagram showing a detection mark and a non-target image according to a first modification;

FIG. 7 is a diagram showing a detection mark and a 45 non-target image according to a second modification;

FIG. 8 is a diagram showing a detection mark according to a modification;

FIG. 9 is a diagram showing a detection mark according to a modification; and

FIG. 10 is a diagram showing a detection mark according to a modification.

DETAILED DESCRIPTION

55 An example of an exemplary embodiment of the present invention will be described below with reference to the drawings.

(Inkjet Recording Apparatus 10)

First, an inkjet recording apparatus 10 will be described. 60 FIG. 1 is a schematic diagram showing a configuration of the inkjet recording apparatus 10.

The inkjet recording apparatus 10 shown in FIG. 1 is an example of an ejection apparatus that ejects droplets. Specifically, the inkjet recording apparatus 10 ejects ink droplets 65 to a recording medium. More specifically, as shown in FIG. 1, the inkjet recording apparatus 10 ejects ink droplets to a continuous sheet P (an example of the recording medium) to

form an image on the continuous sheet P. In other words, the inkjet recording apparatus 10 is also an example of an image forming apparatus that forms an image on a recording medium. The continuous sheet P is an elongated recording medium having a length in a feeding direction of the continuous sheet to be fed. Specifically, the continuous sheet P is also a kind of paper in which plural pages are arranged along the feeding direction.

As shown in FIG. 1, the inkjet recording apparatus 10 includes a feeding mechanism 20, an ejection mechanism 30, sensing units 41, 42, and 43, and a control device 16. Hereinafter, specific configurations of the units (the feeding mechanism 20, the ejection mechanism 30, the sensing units 41, 42, and 43, and the control unit 16) of the inkjet recording apparatus 10 will be described.

(Feeding Mechanism 20)

The feeding mechanism 20 shown in FIG. 1 is an example of a feeding unit that feeds a recording medium. Specifically, the feeding mechanism 20 is a mechanism for feeding the continuous sheet P. More specifically, as shown in FIG. 1, the feeding mechanism 20 includes a wind-off roller 22, a wind-up roller 24, plural winding rollers 26, and plural support rollers 27.

The wind-off roller 22 is a roller for unwinding the continuous sheet P. The continuous sheet P is previously wound around the wind-off roller 22. The winding roller 22 unwinds the wound continuous sheet P via rotation.

The plural winding rollers 26 are rollers around which the continuous sheet P is wound and stretched. Specifically, the plural winding rollers 26 wind around the continuous sheet P, between the wind-off roller 22 and the wind-up roller 24. Accordingly, a feeding path of the continuous sheet P from the wind-off roller 22 to the wind-up roller 24 is determined. Each of the plural support rollers 27 is a roller for supporting the continuous sheet P on a lower side of each of ejection heads 32Y, 32M, 32C, and 32K in the ejection mechanism 30 to be described below.

The wind-up roller 24 is a roller for winding up the continuous sheet P thereon. The wind-up roller 24 is driven by a drive unit 28 to rotate. As a result, the wind-up roller 24 winds up the continuous sheet P, and simultaneously, the wind-off roller 22 unwinds the continuous sheet P. Then, the continuous sheet P is wound up by the wind-up roller 24 and is fed by being unwound by the wind-off roller 22. The plural winding rollers 26 and the plural support rollers 27 rotate following the continuous sheet P being fed. In the drawings, the feeding direction of the continuous sheet P (hereinafter, sometimes referred to as a "paper feeding direction") is indicated by an arrow A as appropriate.

The configuration of the feeding mechanism 20 is not limited to the above-described configuration. For example, the feeding mechanism 20 may have a configuration such that the continuous sheet P may be fed from a storage unit in which the continuous sheet P is accommodated in a folded state to a storage unit in which the continuous sheet P is to be accommodated so as to be folded. The feeding mechanism 20 may have a configuration in which a pair of feeding rollers, a feeding belt, or the like may be used as a feeding member that feeds the continuous sheet P.

Further, the continuous sheet P is used as the recording medium in the present exemplary embodiment, but the present invention is not limited thereto. For example, cut paper may be used as the recording medium.

(Ejection Mechanism 30)

The ejection mechanism 30 shown in FIG. 1 is a mechanism for ejecting ink droplets as an example of liquid droplets. Specifically, the ejection mechanism 30 ejects ink

droplets onto the continuous sheet P fed by the feeding mechanism 20 to form an image. More specifically, as shown in FIG. 1, the ejection mechanism 30 includes ejection heads 32Y, 32M, 32C, and 32K (hereinafter, referred to as 32Y to 32K).

Each of the ejection heads 32Y to 32K is a head that ejects ink droplets. Specifically, each of the ejection heads 32Y to 32K ejects ink droplets of respective colors of yellow (Y), magenta (M), cyan (C), and black (K) onto the continuous sheet P to form an image on the continuous sheet P. More specifically, each of the ejection heads 32Y to 32K is configured as follows.

As shown in FIG. 1, the ejection heads 32Y to 32K are disposed in this order toward an upstream side in the paper feeding direction. Each of the ejection heads 32Y to 32K has a length in a width direction of the continuous sheet P (hereinafter, sometimes referred to as "paper width direction"). The paper width direction is a direction which intersects the paper feeding direction (specifically, a direction which is orthogonal to the paper feeding direction).

Each of the ejection heads 32Y to 32K has a nozzle surface 30S on which a nozzle 30N is formed. The nozzle surfaces 30S of the ejection heads 32Y to 32K face downward and face the continuous sheet P fed by the feeding mechanism 20. Each of the ejection heads 32Y to 32K ejects ink droplets from the nozzle 30N to the continuous sheet P according to a known method such as a thermal method and a piezoelectric method.

Examples of the ink used in each of the ejection heads 32Y to 32K include aqueous ink and oily ink. The aqueous ink contains, for example, a solvent containing water as a main component, and a colorant (specifically, a pigment or a dye), and other additives. The oily ink includes, for example, an organic solvent, a colorant (specifically, a pigment or a dye), and other additives.

Here, the ejection head 32K is an example of a first ejection unit. The ejection head 32K ejects ink droplets onto the continuous sheet P to form a normal image 70 and plural detection marks 80 as shown in FIG. 2. In other words, the detection marks 80 are formed by the ejection head disposed at the most upstream side in the paper feeding direction.

The normal image 70 is an image formed on an image area R of each page of the continuous sheet P. The normal image 70 is also an image formed based on an instruction of image formation that is input via a user terminal or the like. More specifically, the normal image 70 is also an image formed based on image data acquired by the control device 16 together with the image formation instruction.

On the other hand, the plural detection marks 80 are an example of a detection image, and are images formed outside the image areas R of pages of the continuous sheet P, respectively. The plural detection marks 80 are images detected by the sensing units 41, 42, and 43. More specifically, the plural detection marks 80 are also images formed regardless of image data acquired by the control device 16 together with an instruction of image formation. In other words, the plural detection marks 80 can be formed in a predetermined pattern based on pre-stored image data.

In the present exemplary embodiment, as shown in FIG. 2, the ejection head 32K forms plural (specifically, for example, 10) detection marks 80 along the paper feeding direction. Specifically, the ejection head 32K forms, for example, nine first detection marks 81 and one second detection mark 82 as the plural detection marks 80. In other words, the plural detection marks 80 include nine first detection marks 81 and one second detection mark 82. The plural detection marks 80 are formed for each page of the

continuous sheet P. The first detection mark **81** is an example of a first detection image. The second detection mark **82** is an example of a second detection image.

Each of the first detection marks **81** and the second detection mark **82** are formed into a rectangular shape elongated in the paper width direction. That is, each of the first detection marks **81** and the second detection mark **82** are formed into a rectangular shape in which the paper width direction is a longitudinal direction and the paper feeding direction is a lateral direction.

The second detection mark **82** is disposed on the downstream side relative to the nine first detection marks **81** in the paper feeding direction. In other words, the second detection mark **82** is disposed on the most downstream side in the paper feeding direction among the plural detection marks **80**.

The nine first detection marks **81** are formed in congruent rectangular shapes. That is, each of the nine first detection marks **81** has a rectangular shape in which a dimension along the paper feeding direction (hereinafter, referred to as "feeding-direction length") is the same as a dimension along the paper width direction (hereinafter, referred to as "width-direction length").

The feeding-direction length of the second detection mark **82** is larger than the feeding-direction length of the first detection mark **81**. In other words, the feeding-direction length of the second detection mark **82** is maximized in the plural detection marks **80**. The width-direction length of the second detection mark **82** is the same as the width-direction length of the first detection mark **81**.

The respective first detection marks **81** and the second detection mark **82** are overlapped with each other when viewed in the paper feeding direction. More specifically, two ends of each of the first detection marks **81** in the paper width direction are aligned with those of the second detection mark **82** when viewed in the paper feeding direction.

The second detection mark **82** and a first detection mark **81** which is adjacent to the second detection mark **82** are arranged with a gap interposed therebetween in the paper feeding direction. In addition, the nine first detection marks **81** are arranged with respective gaps interposed therebetween in the paper feeding direction. In other words, respective margin portions **90** are provided between two adjacent detection marks among the second detection mark **82** and the nine first detection marks **81**. The feeding-direction lengths of the margin portions **90** are the same. That is, the feeding-direction lengths of the plural margin portions **90** are constant. Further, the feeding-direction length of each of the margin portions **90** is the same as the feeding-direction length of the first detection mark **81**.

The margin portion **90** is an area having a boundary that can be detected by the sensing units **41**, **42**, **43** relative to the second detection mark **82** and each of the first detection marks **81**. It should be noted that no image is formed in the margin portions **90**.

On the other hand, each of the ejection heads **32C**, **32M**, and **32Y** is an example of a second ejection unit. The ejection heads **32C**, **32M**, and **32Y** eject ink droplets onto the continuous sheet P at a timing determined as described below by the control device **16**.

Any one or two of the ejection heads **32C**, **32M**, and **32Y** may be regarded as an example of the second ejection unit. Therefore, in the present exemplary embodiment, when the ejection head **32K** is an example of the first ejection unit, at least one of the ejection heads **32C**, **32M**, and **32Y** can be used as an example of the second ejection unit.

(Sensing Units **41**, **42**, and **43**)

The sensing units **41**, **42**, and **43** shown in FIG. 1 senses the second detection mark **82** and the nine first detection marks **81**, and are disposed between the ejection heads, respectively. Specifically, the sensing units **41**, **42**, and **43** sense at least a front end of the second detection mark **82** and each of the nine first detection marks **81**. The front end is a downstream end in the paper feeding direction. The sensing units **41**, **42**, and **43** include, for example, a reflection optical sensor.

The sensing unit **41** is disposed between the ejection head **32K** and the ejection head **32C** in the paper feeding direction. That is, the sensing unit **41** is disposed on the downstream side relative to the ejection head **32K** in the paper feeding direction and on the upstream side relative to the ejection head **32C** in the paper feeding direction. Specifically, the sensing unit **41** is disposed at a position closer to the ejection head **32C** relative to the ejection head **32K**. The sensing unit **41** may be disposed at a position which has the same distance from the ejection head **32K** and the ejection head **32C**, or at a position closer to the ejection head **32K** relative to the ejection head **32C**.

The sensing unit **42** is disposed between the ejection head **32C** and the ejection head **32M** in the paper feeding direction. That is, the sensing unit **42** is disposed on the downstream side relative to the ejection head **32C** in the paper feeding direction and on the upstream side relative to the ejection head **32M** in the paper feeding direction. Specifically, the sensing unit **42** is disposed at a position closer to the ejection head **32M** relative to the ejection head **32C**. The sensing unit **42** may be disposed at a position has the same distance from the ejection head **32C** and the ejection head **32M**, or at a position closer to the ejection head **32C** relative to the ejection head **32M**.

The sensing unit **43** is disposed between the ejection head **32M** and the ejection head **32Y** in the paper feeding direction. That is, the sensing unit **43** is disposed on the downstream side relative to the ejection head **32M** in the paper feeding direction and on the upstream side relative to the ejection head **32Y** in the paper feeding direction. Specifically, the sensing unit **43** is disposed at a position closer to the ejection head **32Y** relative to the ejection head **32M**. The sensing unit **43** may be disposed at a position has the same distance from the ejection head **32M** and the ejection head **32Y**, or at a position closer to the ejection head **32M** relative to the ejection head **32Y**.

(Control Device **16**)

The control device **16** shown in FIG. 1 controls an operation of each part of the inkjet recording apparatus **10**. Specifically, the control device **16** includes a storage unit including a ROM, a storage, or the like in which a program is stored, and a processor that operates according to a program. The control device **16** reads and executes a program and table information stored in the storage unit, thereby controlling the operation of each unit of the inkjet recording apparatus **10**.

When the above-described program is executed, the control device **16** realizes various functions by using hardware resources such as a storage unit and a processor. As shown in FIG. 1, the control device **16** includes a detection unit **17** and a control unit **18** that controls driving of the ejection heads **32Y** to **32K** as a functional configuration.

The detection unit **17** detects each distance from a predetermined origin of the continuous sheet P to the second detection mark **82** and each of the nine first detection marks **81** along the feeding direction. Specifically, the detection unit **17** detects the distance as follows.

As shown in FIG. 3, the detection unit 17 generates a clock signal. Further, the detection unit 17 calculates a distance X_1 from the origin O to the second detection mark 82 based on the count of the clock signals from the predetermined origin (hereinafter, sometimes referred to as "origin O") of the continuous sheet P to the front end of the second detection mark 82 detected by the sensing unit 41.

Further, the distance from the origin O to each of the first detection marks 81 is calculated from the count of clock signals from the origin O to the front end of each of the first detection marks 81 detected by the sensing unit 41. By calculating in this manner, the detection unit 17 acquires ten detection values.

In FIG. 3, a detection value of the distance from the origin O to the second detection mark 80 (that is, a first detection mark 81 in the first place) is indicated by "X2", and a detection value of the distance from the origin O to the n-th detection mark 80 is indicated by "Xn". The "second" and "n-th" described above are the order when the ten detection marks 80 (the second detection mark 82 and the nine first detection marks 81) are counted from the downstream side to the upstream side in the paper feeding direction. In FIG. 3, a detection signal obtained by detecting the second detection mark 82 and each of the nine first detection marks 81 by means of the sensing unit 41 is shown as a detection signal Q.

The predetermined origin O of the continuous sheet P is, for example, a front end of each page of the continuous sheet P. The origin O is detected, for example, by detecting a mark, which is attached to the continuous sheet P in advance, by the sensing unit 41.

Here, in the control device 16, ten predetermined setting values of distances from the predetermined origin O of the continuous sheet P to the second detection mark 82 and each of the nine first detection marks 81 are stored in the storage unit.

In FIG. 3, a setting value of a distance from the origin O to the second detection mark 82 is indicated by "M1", and a setting value of a distance from the origin O to the second detection mark 80 (that is, a first detection mark 81 in the first place) is indicated by "M2". In FIG. 3, a setting value of a distance from the origin O to the n-th first detection mark 81 is indicated by "Mn".

Then, the control unit 18 of the control device 16 causes the ejection head 32C to eject at a timing based on an addition value obtained by adding an average value of differences between detection values of the detection unit 17 and setting values to a setting value in the second detection mark 82.

Specifically, the ejection head 32C ejects ink droplets onto the continuous sheet P at a timing corresponding to a value obtained by adding a predetermined reference distance T to the addition value. The reference distance T is defined by a distance from the sensing unit 41 to the ejection head 32C and a position where formation of an image is started in each page of the continuous sheet P.

In FIG. 3, a difference (error) between a detection value X_1 and a setting value M1 is indicated by " Δ_1 ", a difference between a detection value X_2 and a setting value M2 is indicated by " Δ_2 ", and a difference between a detection value X_n and a setting value M_n is indicated by " Δ_n ". In FIG. 3, the average value of the differences between detection values and setting values is represented by " Δ_{AVE} ", and the addition value is indicated by " $M1+\Delta_{AVE}$ ".

Examples of factors for the difference (error) between the detection value X_n and the setting value M_n include the elongation of the continuous sheet P in the paper feeding

direction due to swell of the continuous sheet P containing the ink, and a sensing error of the sensing unit 41 (specifically, variation in response time of the sensing unit 41).

Similar to the manner as described above, the control device 16 uses sensing results of the sensing unit 42 to cause the ejection head 32M to eject at a timing based on an addition value obtained by adding an average value of differences between the detection values of the detection unit 17 and setting values to a setting value in the second detection mark 82. Further, similar to the manner as described above, the control device 16 uses detection results of the sensing unit 43 to cause the ejection head 32Y to eject at a timing based on an addition value obtained by adding an average value of differences between the detection values of the detection unit 17 and setting values to the setting value in the second detection mark 82.

Effects of Present Exemplary Embodiment

20 In the present exemplary embodiment, as described above, the detection unit 17 detects distances X_1 to X_{10} from the predetermined origin O of the continuous sheet P to the second detection mark 82 and the nine first detection marks 81, respectively (see FIG. 4A). The ejection head 32C ejects ink droplets onto the continuous sheet P at a timing based on an addition value obtained by adding an average value of differences between detection values of the detection unit 17 and setting values to the setting value in the second detection mark 82.

25 Here, when the distances X_1 to X_{10} from the origin O to the second detection mark 82 and the nine first detection marks 81 are calculated by detecting a distance X_1 from the origin O to the second detection mark 82, and a distance ΔX between the second detection mark 82 and the nine first detection marks 81, and adding the detection value ΔX to the detection value X_1 (comparative example, see FIG. 4B), 30 position shift between an ejection position of the ejection head 32K to the continuous sheet P and an ejection position of the ejection head 32C to the continuous sheet P may 35 become large (see FIG. 5). In particular, since the detection error (specifically, the variation in response time of the sensing unit 41) of the sensing unit 41 accumulates, the error increases.

30 In contrast, since the distances X_1 to X_{10} from the origin O to the second detection mark 82 and the nine first detection marks 81 are detected respectively in the present exemplary embodiment, the position shift between the ejection position of the ejection head 32K to the continuous sheet P and the ejection position of the ejection head 32C to the continuous sheet P is reduced, as compared with the comparative example described above. In particular, the detection error of the sensing unit 41 (specifically, variation in response time of the sensing unit 41) is not accumulated, and an error due to a detection error of the sensing unit 41 45 decreases (see FIG. 5).

40 In the present exemplary embodiment, the feeding-direction length of the second detection mark 82 disposed on the downstream side relative to the nine first detection marks 81 in the paper feeding direction is larger than the feeding-direction length of the first detection mark 81.

45 Therefore, as compared with a configuration in which the feeding-direction lengths of the plural detection marks 80 (nine first detection marks 81 and the second detection mark 82) is constant, the detection failure of the second detection mark 82 disposed on the downstream side relative to the nine first detection marks 81 in the paper feeding direction is prevented because the feeding-direction length of the second

detection mark **82** is larger than the feeding-direction length of the first detection mark **81**.

In particular, in the present exemplary embodiment, the feeding-direction length of the second detection mark **82** on the most downstream side in the paper feeding direction is larger than that of another detection mark **80** (nine first detection marks **81**). Therefore, as compared with a configuration in which the feeding-direction length of the second detection mark **82** on the most downstream side in the paper feeding direction is smaller than that of another detection mark **80** (nine first detection marks **81**), a detection failure of the second detection mark **82** on the most downstream side in the paper feeding direction is prevented.

(First Modification)

In the present exemplary embodiment, an image is not formed in each of the margin portions **90**, but the present invention is not limited thereto. For example, as shown in FIG. 6, the ejection head **32K** may form plural detection marks **80** (the second detection mark **82** and the nine first detection marks **81**) in the paper feeding direction such that a non-target image **99** that is not detected by the detection unit **17** is disposed in the margin portion **90**. An example of the non-target image **99** includes an image such as a mark called a register mark. In FIG. 6, a part of the non-target image **99** (specifically, a vertical line **99A**) is disposed in the margin portion **90**. The control device **16** does not have a setting value corresponding to the non-target image **99**. In other words, the non-target image **99** can be said to be an image for which the control device **16** does not have a setting value.

The non-target image **99** is disposed in the margin portion **90** in the first modification, so that space may be saved on the continuous sheet **P** as compared with the configuration in which the non-target image **99** is disposed outside the margin portion **90**.

(Second Modification)

The ejection head **32K** may form plural detection marks **80** (second detection mark **82** and nine first detection marks **81**) in the paper feeding direction such that a first margin portion **91** and a second margin portion **92** larger than the first margin portion **91** in which the non-target image **99** is disposed are formed as a margin portion **90** as shown in FIG. 7 based on the configuration of the first modification. In FIG. 7, the vertical line **99A** and a horizontal line **99B** of the non-target image **99** are disposed in the second margin portion **92**.

The non-target image **99** is disposed in the second margin portion **92** in the second modification, so that the space may be saved on the continuous sheet **P** as compared with the configuration in which the non-target image **99** is disposed in the second margin portion **91**.

(Other Modifications)

In the present exemplary embodiment, the feeding-direction length of the second detection mark **82** is larger than the feeding-direction length of the first detection mark **81**, but the present invention is not limited thereto. For example, as shown in FIG. 8, the plural detection marks **80** may have a constant feeding-direction length.

In the present exemplary embodiment, the feeding-direction lengths of the plural margin portions **90** are constant, but the present invention is not limited thereto. For example, as shown in FIG. 9, the feeding-direction lengths of the plural margin portions **90** may be partially or entirely different.

In the present exemplary embodiment, the feeding-direction length of the second detection mark **82** disposed on the most downstream side in the paper feeding direction is the maximum in the plural detection marks **80**, but the present

invention is not limited thereto. For example, as shown in FIG. 10, in the plural detection marks **80**, the feeding-direction lengths of the second and subsequent detection marks **80** may be maximized, counting from the most downstream side in the paper feeding direction. More specifically, the feeding-direction lengths of the plural detection marks **80** may be partially or entirely different, and the feeding-direction lengths of the plural margin portions **90** may be partially or entirely different.

Further, ten detection marks **80** are formed as the plural detection marks **80** in the present exemplary embodiment, but the present invention is not limited thereto. For example, two to nine detection marks **80**, or eleven or more detection marks **80** may be formed as the plural detection marks **80**.

The present invention is not limited to the above exemplary embodiment, and various modifications, changes and improvements can be made without departing from the scope of the invention. For example, the modifications shown above may be combined with each other as appropriate.

What is claimed is:

1. An ejection apparatus comprising:
a feeding unit that feeds a recording medium;
a first ejection unit that ejects droplets onto the recording medium to form a plurality of detection images along a feeding direction of the recording medium,
a detection unit that detects a distance from a predetermined origin of the recording medium to each of the detection images along the feeding direction; and
a second ejection unit that is disposed on a downstream side relative to the first ejection unit in the feeding direction of the recording medium, and ejects droplets onto the recording medium at a timing based on a value obtained by adding an average value of differences between detection values of the detection unit and setting values to a setting value of the detection image on most downstream side in the feeding direction.

2. The ejection apparatus according to claim 1, wherein the first ejection unit forms, as the plurality of detection images, a first detection image and a second detection image that is disposed on a downstream side in the feeding direction relative to the first detection image and has a dimension along the feeding direction larger than that of the first detection image.

3. The ejection apparatus according to claim 2, wherein the first ejection unit forms the second detection image that is disposed on most downstream side in the feeding direction and has a maximum dimension along the feeding direction.

4. The ejection apparatus according to claim 3, wherein the detection unit detects the distance along the feeding direction based on detection signals of the detection images from a sensing unit disposed between the first ejection unit and the second ejection unit.

5. The ejection apparatus according to claim 3, wherein the first ejection unit forms the plurality of detection images in the feeding direction such that an image that is not a detection target of the detection unit is disposed in a margin portion between the detection images.

6. The ejection apparatus according to claim 5, wherein the first ejection unit forms the plurality of detection images along the feeding direction such that a first margin portion, and a second margin portion which is larger than the first margin portion and in which an image that is not a detection target of the detection unit is disposed are formed as the margin portion.

7. The ejection apparatus according to claim 6, wherein the detection unit detects the distance along the feeding

11

direction based on detection signals of the detection images from a sensing unit disposed between the first ejection unit and the second ejection unit.

8. The ejection apparatus according to claim **5**, wherein the detection unit detects the distance along the feeding direction based on detection signals of the detection images from a sensing unit disposed between the first ejection unit and the second ejection unit.

9. The ejection apparatus according to claim **2**, wherein the first ejection unit forms the plurality of detection images in the feeding direction such that an image that is not a detection target of the detection unit is disposed in a margin portion between the detection images.

10. The ejection apparatus according to claim **9**, wherein the first ejection unit forms the plurality of detection images along the feeding direction such that a first margin portion, and a second margin portion which is larger than the first margin portion and in which an image that is not a detection target of the detection unit is disposed are formed as the margin portion.

11. The ejection apparatus according to claim **10**, wherein the detection unit detects the distance along the feeding direction based on detection signals of the detection images from a sensing unit disposed between the first ejection unit and the second ejection unit.

12. The ejection apparatus according to claim **9**, wherein the detection unit detects the distance along the feeding direction based on detection signals of the detection images from a sensing unit disposed between the first ejection unit and the second ejection unit.

13. The ejection apparatus according to claim **2**, wherein the detection unit detects the distance along the feeding

12

direction based on detection signals of the detection images from a sensing unit disposed between the first ejection unit and the second ejection unit.

14. The ejection apparatus according to claim **1**, wherein the first ejection unit forms the plurality of detection images in the feeding direction such that an image that is not a detection target of the detection unit is disposed in a margin portion between the detection images.

15. The ejection apparatus according to claim **14**, wherein the detection unit detects the distance along the feeding direction based on detection signals of the detection images from a sensing unit disposed between the first ejection unit and the second ejection unit.

16. The ejection apparatus according to claim **14**, wherein the first ejection unit forms the plurality of detection images along the feeding direction such that a first margin portion, and a second margin portion which is larger than the first margin portion and in which an image that is not a detection target of the detection unit is disposed are formed as the margin portion.

17. The ejection apparatus according to claim **16**, wherein the detection unit detects the distance along the feeding direction based on detection signals of the detection images from a sensing unit disposed between the first ejection unit and the second ejection unit.

18. The ejection apparatus according to claim **1**, wherein the detection unit detects the distance along the feeding direction based on detection signals of the detection images from a sensing unit disposed between the first ejection unit and the second ejection unit.
